CONTINUOUS SERIES OF ENVELOPES
Albert H. Johnson, 4 James St., Enfield, Conn.
Filed June 16, 1964, Ser. No. 375,602
6 Claims. (Cl. 229—69)

This invention relates to a series of envelopes arranged in a continuous series for feeding successively to an addressing machine, or typewrite or the like.

The invention is in certain respects an improvement on the subject matter of applicant's copending application Serial No. 328,364, filed December 5, 1963.

Where manifolded envelopes are fed between a platen and a printing mechanism, particularly in high speed addressing machines, for example, the leading edge of individual envelopes may be caught by guide fingers or other projecting elements which are located close to the path of the envelope. When this occurs the envelope or the carrying strip may be torn or the machine may be jammed. The principal feature of this invention is an arrangement of the manifolded envelope to avoid this objection. Another feature is an arrangement by which to shield the leading edge of the envelope so that it will be guided past any of these projecting devices.

More specifically one feature of the invention is the formation of spaced flaps in the carrying strip in a position to overlie the leading edges of successive envelopes. Another feature is the use of these flaps in locating the envelopes on the backing strip during the assemblage of envelopes and tapes on the backing strip.

Other features and advantages will be apparent from the specification and claims, and from the accompanying drawings which illustrate an embodiment of the invention.

FIG. 1 is a plan view showing a continuous series of standard envelopes.

FIG. 2 is a sectional view along line 2—2 of FIG. 1.

FIG. 3 is a plan view similar to FIG. 1 of a modification.

FIG. 4 is a plan view similar to FIG. 1 of another modification.

Referring first to FIGS. 1 and 2, each envelope 2 is a standard envelope having a front panel 4 and a back panel consisting of side flaps 6 and 8, a bottom flap 10 and a sealing flap 12. The latter flap 12 is folded against but not adhered to the remainder of the back panel. The envelope, as described, is a standard form of mailing envelope which is produced in very large quantities and is commonly known in the trade as one of the standard forms.

The series of envelopes 2 are arranged in spaced relation in a continuous series on a continuous backing strip 14 and are maintained in spaced relation to each other on the backing strip by spaced tapes 16 and 18 which overlie the opposite ends of the envelope and form pockets 20 to receive the ends of the envelope when the tapes are pressed into contact with the backing strip. The opposite edges of the backing strip project beyond the tapes and have a row of perforations 22 for use in feeding the assemblage to a machine. The tapes 16 and 18 have adhesive 24 on the underside thereof of the conventional latex type or heat sealing type and the backing strip has cooperating bands of adhesive 26. In this way the adhesive on the tapes will adhere to the adhesive on the backing strip where it is not covered by the ends of the envelopes, thereby forming the pockets 20 for the ends of the envelopes but without adhering directly to the envelopes. The envelopes are spaced apart by spacers 28 between the ends of adjacent envelopes where the tapes and the backing strip are held together.

To conceal the leading edge of each of the envelopes, and thus protect it from contact with adjacent parts of

2

the machine as it is fed through by the backing strip, the latter has a flap 30 cut therein for each envelope, the flap being substantially equal to the spacing between the tapes and of a substantial length to overlie a major portion of the envelope. This flap 30 serves to conceal the leading edge 32 of the envelope and provide a smooth surface such that projecting elements on the machine closely adjacent to the front surface of the backing strip will not be caught on the leading edge of the envelope as the assemblage is fed in the direction of the arrow 33 through the machine.

The flap is formed by a U-shaped slit cut in the backing strip and the ends 34 of the slit are engaged by the leading edge of the envelope, as shown. This arrangement serves to locate each of the envelopes in the precise position lengthwise of the backing strip and also accurately with the long edges of the envelope at right angles to the edges of the strip since the envelopes are positioned beneath these flaps during assemblage of the envelopes on the backing strip and beneath the tapes.

The flap 30 is shown as being slightly wider than the spacing of the inner edges of the tapes so that the opposite edges of the flap are engaged by the tapes, as shown. This arrangement provides a secure attachment of the flap and makes sure that the flap will be in a position to receive whatever information is applied to the envelope by the machine. In this way the flap may also serve as a permanent record of whatever information was applied to the envelope. As will be apparent, the back of the flap 30 may carry transfer material, such as carbon paper or the equivalent in order that the information printed on the flap will also be carried onto the surface of the envelope.

The flap that overlies the envelope may be made smaller as shown in FIG. 3, where the flap 36 is formed by an arcuate slit in the backing strip 14' and the ends 38 of the slit terminate at points spaced from the side tapes 16' and 18'. The envelopes 2' are located by the ends of the slit as above described, and the flap serves to cover the leading edge of the envelope. Obviously, this flap 36 is not intended to receive any of the information being printed; however, it does serve to protect the leading edge of the envelope, as above described.

As shown in FIG. 4, the flap 40 is longer and terminates just under the inner edges of the tapes 16" and 18" and is thus held in position to some extent by these tapes. The ends 42 of the slit that formed the flap serve as before to locate the envelopes both endwise of the backing strip 14" and in proper oriented position thereon before the tapes 16" and 18" are applied. The flap 40 also serves the function of covering the leading edge of the envelope so that any projecting elements forming part of the machine cannot catch the leading edge of the envelope.

It will be understood that this type of manifold envelope is arranged to feed over a platen with the printing mechanism on the front side of the backing mechanism. Thus the concealment of the leading edge of the envelope from the front side of the assemblage serves the desired purpose. In the usual machine the platen side of the device does not have projecting elements that would readily catch on the envelope.

The effect of the flap 30, 36 or 40 is to hold the leading edge of the envelope smoothly against the backing strip in the area of the machine where the envelope might be caught. Thus, the overlying flap can be as small as desired provided it is located in such a way as to keep the envelope flat against or substantially in the plane of the backing strip.

It is to be understood that the invention is not limited to the specific embodiment herein illustrated and described, but may be used in other ways without departure from its spirit as defined by the following claims.

I claim:

1. A series of envelopes arranged in spaced relation to one another for feeding continuously and successively to a machine, a backing strip on which the envelopes are positioned, tapes arranged along opposite edges of the series of envelopes to hold them in position on the strip, and means on the backing strip to hold the leading edge of the envelope against the backing strip said means including a flap cut from the portion of the backing strip underlying the envelope, said flap overlying substantially the entire length of the leading edge of the envelope between the tapes.

2. A series of envelopes as in claim 1 in which the flaps extends between the opposite tape and the ends of the flap are engaged by the tapes to hold the flap against the envelope.

3. A device for supporting a series of standard envelopes in spaced relation to one another for continuously and successively feeding the envelopes to an addressing machine or the like, including a backing strip on which the envelopes are positioned in spaced relation, the forward edge of the envelope in the direction of movement of the backing strip into the machine being the leading edge, tapes extending lengthwise of the strip in spaced relation to one another and overlying the opposite ends of the envelopes to hold the envelopes in position on the strip, and a plurality of flaps integral with the backing strip and overlying substantially the entire length of the leading

edges of the spaced envelopes being formed by slits cut in the backing strip in the area underneath the envelope, the ends of each slit engaging the leading edge of the associated envelope adjacent opposite ends and locating it lengthwise on the backing strip.

5. A device as in claim 3 in which the slit is U-shaped and the ends of the slit extend in the direction of feeding motion of the strip into the machine.

10 6. A device as in claim 3 in which the backing strip and tapes cooperate to form pockets to receive the ends of the envelope and the ends of the flap are engaged by the tapes.

15 7. A device as in claim 3 in which the flap extends across the envelope between the tapes, and the ends of the flaps are positioned beneath and retained by the tapes.
